(57) CLAIM

The ornamental design for a vehicle screen set, as shown and described.

DESCRIPTION

FIG. 1 is a front elevational view of a vehicle screen set. FIG. 2 is an end view of a long side of each of the screens according to the screen set of FIG. 1, the end view of the opposing long side being a mirror image of the end view shown; and,

FIG. 3 is an end view of a short side of each of the screens according to the screen set of FIG. 1, the end view of the opposing short side being a mirror image of the end view shown.
